[57] CLAIM

The ornamental design for the telephone dialer card, as shown and described.

DESCRIPTION

FIG. 1 is a top plan view of a telephone dialer card showing my new design;

FIG. 2 is an edge elevational view, the opposite edge being a mirror image thereof;

FIG. 3 is an end elevational view, the opposite end being a mirror image thereof;

FIG. 4 is a bottom plan view thereof;

FIG. 5 is an edge elevational view of a second embodiment of the telephone dialer card shown in FIG. 1, the opposite edge being a mirror image thereof;

FIG. 6 is a top plan view thereof; and,

FIG. 7 is a bottom plan view thereof.

The end elevations of the second embodiment are plain and unornamented.

FIG. 1

FIG. 3

FIG. 2

FIG. 4

FIG. 5

FIG. 6

FIG. 7
